WEB ROLL SUPPORTING AND CONTROLLING
MECHANISMRobert Alonzo Williams, Chicago, Ill., assignor to
Ditto, Incorporated, Chicago, Ill., a corporation
of West Virginia

Application August 9, 1941, Serial No. 406,210

6 Claims. (Cl. 242—68)

This invention relates to means for supporting and controlling web rolls, and it has for its object the provision of a new and improved form and arrangement of parts by which a roll can be very quickly and easily placed in operative position in a machine and by which a frictional control of the roll shall be established so as to prevent over-running of the roll when a short length of the web is drawn from the roll by a pull on the web. The invention is designed particularly for use in a machine of the type disclosed by my prior Letters Patent No. 2,238,356, of April 15, 1941, in which a comparatively large number of webs are employed, with the rolls arranged in fairly close proximity to each other.

In the preferred form of the invention, a web roll is supported on a shaft between two pressure plates by which a frictional grip is applied on the faces of the roll, one of the plates being held rigidly in position by means of a set-screw which can readily be loosened for the application of a new web roll, and the other plate being supported yieldingly in position by means of a heavy coiled spring. The preferred means for holding the roll-supporting shaft non-rotatably in position so as to be capable of being quickly and easily applied in position and quickly and easily removed when desired comprises a socket at one side of the machine into which one end portion of the shaft may be moved longitudinally for support and a bearing at the opposite side of the machine into which the opposite end portion of the shaft may be lowered from above for effective engagement therewith, with a locking plate adapted in operative position to hold the shaft rigidly in position in the bearing so as to be non-rotatable therein, and adapted by an easily effected adjustment to be quickly moved to alternative position where it permits the shaft to be lifted freely out of position. It is one of the objects of the invention to provide an improved arrangement by which the position of the locking plate can be controlled to advantage so as to be operable readily by one hand.

It is another object of this invention to improve arrangements of this type in sundry details hereinafter pointed out. The preferred means by which the several objects have been attained are illustrated in the accompanying drawing, in which

Fig. 1 is a transverse vertical sectional view through an embodiment of the preferred form of the invention.

Fig. 2 is a side face view on a considerably en-

larged scale showing the shaft supporting means at one side of the machine.

Fig. 3 is a vertical sectional view on an enlarged scale taken substantially at the line 3—3 of Fig. 1.

Fig. 4 is a horizontal sectional view on an enlarged scale taken substantially at the line 4—4 of Fig. 1; and

Fig. 5 is a horizontal sectional view taken substantially at the line 5—5 of Fig. 2 but with the bracket 15 and shaft 14 omitted for clearance of illustration.

Referring now to the several figures of the drawing, in which corresponding parts are indicated by the same reference characters, 10 and 11 indicate standards formed of sheet metal at opposite sides of the machine, the standard 11 being provided with a socket member 12 adapted to receive the end portion of a shaft 13 therein, as is best shown in Fig. 4.

At the opposite side of the machine, the standard 10 is provided with a curved bearing plate 14 in the form of a channel into which the end portion of the shaft may be lowered from above for effective engagement therewith, the bearing plate

14 being formed on the upper end of a bracket 15 secured by bolts 16 to said standard. This bearing plate 14 is at the same level as that of the socket 12, so as to support the shaft 13 in horizontal position. As is best shown in Fig. 2, the bearing plate 14 is spaced from the face of the standard 10 so as to provide room for two heavy plates 17 and 18 secured to the standard in spaced relation to each other, being rigidly mounted in position by means of machine screws 19. At the

side face of the plate 18, a keeper 19' in the form of an angle is secured by means of machine screws 20, with the flange portion 21 of the keeper wide enough to extend substantially across the space between the plates 17 and 18.

In the slideway provided by the plates 17 and 18 and the keeper 19', a locking plate 22 is slidably mounted, of such width as to engage the inner face of the flange 21 at the upper end of the plate, and of such reduced width at its lower end

45 portion as to have effective engagement with the end face of the shaft 13 for holding the shaft against longitudinal movement and thus preventing withdrawal of the shaft from the socket 12. As is best shown in Fig. 2 where a portion of the shaft 13 is broken away at the left-hand end, the locking plate 22 at its lower end engages a groove 23 in the top face of the shaft 13 so as to hold the shaft securely against rotary movement about its axis. It will be appreciated that with the locking plate 22 in operative holding position as

shown in Fig. 2 the shaft 13 is held firmly in position so as to be non-rotatable and so as to be irremovable from its supporting means.

A novel arrangement of means is provided for controlling the movement of the locking plate 22, comprising a latch bar 24 pivotally mounted in position on the face of the plate 22 by means of a pivot pin 25, such pin 25 being provided with a spring 26 thereon adapted normally to hold the bar swung to the limit of its movement toward the left in Fig. 2. In its effective latching position as shown in Fig. 2, the upper end face of the bar engages a pin 27 carried by the plate 17 so as to be effective for preventing upward movement of the latch bar and the locking plate 22 upon which it is mounted. The bar 24 is provided with a pin 28 serving as a handle for moving the bar and the connected plate. In its edge, the bar 24 is provided with a notch 29 adapted by engagement with the pin 27 to hold the bar 24 and the attached plate 22 in raised position.

With the parts in the positions as illustrated in Fig. 2, whenever the operator desires to remove the shaft from its mountings, he swings the bar 24 toward the right so as to clear the pin 27, after which he raises the bar and attached plate 22, preferably bringing the notch 29 into engagement with said pin 27 for holding the parts in raised position. With the locking plate 22 thus retracted upwardly, the operator is able to lift the shaft 13 and to move it slightly toward the left in Fig. 1 for disengagement of the end portion of the shaft from the socket 12, thus freeing the shaft completely from the supports. When it is desired that the shaft be replaced, the end of the shaft at the right in Fig. 1 is inserted again into the socket 12, after which the opposite end can be positioned readily on the curved supporting plate 14. The pin 28 is then pressed toward the right in Fig. 2 for disengaging the notch 29 from the pin 27, after which the locking plate is moved downwardly again to its operative locking position, with one portion of the lower end of the locking plate engaging the end of the shaft and another portion engaging the groove 23 so as to hold the shaft rigidly in position. Inasmuch as the latch bar 24 can be readily manipulated for either the latching or the unlatching operation, it will be appreciated that the shaft can be very easily removed and then again replaced in operative position.

The means for holding a web roll 30 in position on the shaft 13 and for applying the required frictional grip on the roll for controlling the unrolling operation comprises a pressure plate 31 in the form of a large disc releasably mounted in fixed position on said shaft by means of a set-screw 32 so as to engage one face of the web roll. At the opposite end of the roll 30, a second pressure plate 33 also in the form of a disc is slidably mounted on said shaft so as to be held against rotation thereby, said second pressure plate being pressed yieldingly toward said first named pressure plate by a coiled spring 34 mounted on the shaft between said second pressure plate and a collar 35 secured in adjusted position on the shaft by means of a set-screw 36.

With the collar 35 in the desired adjusted position, and with the point at which the plate 31 is to be secured effectively marked on the shaft, it is an easy matter to apply a fresh roll effectively at the desired point so as to insure proper frictional engagement of the mounting means

with the roll. The shaft is first removed from its supporting means, after which the plate 31 is removed from the shaft so as to permit a fresh roll to be placed in position next to the plate 33. The plate 31 is then secured again in the same position as that at which it had before been mounted, so as to cause the frictional braking effect of the plates 31 and 33 on the interposed web roll to be substantially the same for the new roll as for the former roll.

With the shaft 13 held rigidly in position in the framework, and with the roll 30 held by a frictional grip thereon against free rotary movement with respect to the shaft, the arrangement is such that when the web is drawn off the roll the drag of the gripping plates on the roll prevents any over-running of the roll. The web is thus kept taut between the roll and the means by which a pull is applied on the web, even in cases where the web is drawn off by power applied intermittently.

It has been found in practice that the arrangement shown and described is very satisfactory and is highly successful in use, both with respect to the mounting of the roll in the machine and with respect to the control of the web in operation.

While the form and arrangement of parts as shown and described are preferred, the invention is not to be limited to such construction except so far as the claims may be so limited, it being understood that changes might well be made in the construction without departing from the invention.

I claim:

1. In a web roll control mechanism, the combination of two supports in spaced relation to each other, a shaft movable longitudinally into position to be supported at one end from one of said supports, a bearing member carried by the support at the opposite side of the machine into which the opposite end portion of the shaft may be lowered from above for effective engagement therewith, two heavy plates mounted in spaced relation to each other on said last-mentioned support, a keeper carried by one of said heavy plates having a portion extending opposite to the space between said two plates so as to provide a vertically disposed slideway, and a locking plate slidably mounted in said slideway adapted by engagement with said shaft to hold the shaft rigidly in position.

2. In a web roll control mechanism, the combination of two supports in spaced relation to each other, a shaft movable longitudinally into position to be supported at one end from one of said supports, a bearing member carried by the support at the opposite side of the machine into which the opposite end portion of the shaft may be lowered from above for effective engagement therewith, two heavy plates mounted in spaced relation to each other on said last-mentioned support, a keeper carried by one of said heavy plates having a portion extending opposite to the space between said two plates so as to provide a vertically disposed slideway, a locking plate slidably mounted in said slideway adapted when in lowered position in the slideway to engage said shaft so as to hold it rigidly in position, and readily-releasable means adapted normally to hold said locking plate in its lowered holding position.

3. In a web roll control mechanism, the combination of two supports in spaced relation to each other, a shaft movable longitudinally into

position to be supported at one end from one of said supports, a bearing member carried by the support at the opposite side of the machine into which the opposite end portion of the shaft may be lowered from above for effective engagement therewith, two heavy plates mounted in spaced relation to each other on said last-mentioned support, a keeper carried by one of said heavy plates having a portion extending opposite to the space between said two plates so as to provide a vertically disposed slideway, a locking plate slideable vertically in said slideway adapted when in lowered position in the slideway to engage said shaft so as to hold it rigidly in position, and a latch member movably mounted on said locking plate adapted by engagement with a fixed bearing on said slideway to hold said locking plate normally in its lowered holding position.

4. In a web roll control mechanism, the combination of two supports in spaced relation to each other, a shaft movable longitudinally into position to be supported at one end from one of said supports, a bearing member carried by the support at the opposite side of the machine into which the opposite end portion of the shaft may be lowered from above for effective engagement therewith, two heavy plates mounted in spaced relation to each other on said last-mentioned support, a keeper carried by one of said heavy plates having a portion extending opposite to the space between said two plates so as to provide a vertically disposed slideway, a locking plate slideable vertically in said slideway adapted when in lowered position in the slideway to engage said shaft so as to hold it rigidly in position, and a latch member pivotally mounted on said locking plate adapted by engagement with a pin carried by one of said spaced plates to hold said locking plate normally pressing said latch member into holding position.

5. In a web roll control mechanism, the combination of two supports in spaced relation to each other, a shaft movable longitudinally into position to be supported at one end from one

of said supports, a bearing member carried by the support at the opposite side of the machine into which the opposite end portion of the shaft may be lowered from above for effective engagement therewith, two heavy plates mounted in spaced relation to each other on said last-mentioned support, a keeper carried by one of said heavy plates having a portion extending opposite to the space between said two plates so as to provide a vertically disposed slideway, a locking plate slideable vertically in said slideway adapted when in lowered position in the slideway to engage said shaft so as to hold it rigidly in position, and a latch member pivotally mounted on said locking plate adapted by engagement with a fixed bearing on said slideway to hold said locking plate normally in its lowered holding position and adapted by engagement of a notch in its face with a portion of said slideway to hold said locking plate normally in its raised position.

6. In a web roll control mechanism, the combination of two supports in spaced relation to each other, a shaft movable longitudinally into position to be supported at one end from one of said supports, a bearing member carried by the support at the opposite side of the machine into which the opposite end portion of the shaft may be lowered from above for effective engagement therewith, a locking member slidably mounted in position above said bearing member in the form of a bar having a notch in its lower end adapted by engagement with said shaft to hold the shaft against longitudinal movement and adapted by engagement with an opening in the face of the shaft to hold the shaft against either vertical movement or rotary movement, and a latch member movably mounted on said locking member adapted normally by engagement with a fixed portion of the structure to hold said locking member normally in operative locking position.

ROBERT ALONZO WILLIAMS.
